CLAIM

The ornamental design for a strain relief for a cable connector as shown and described.

DESCRIPTION

FIG. 1 is a top perspective view of a strain relief for a cable connector showing our new design;

FIG. 2 is top view thereof;

FIG. 3 is a left side view thereof;

FIG. 4 is a right side view thereof;

FIG. 5 is a bottom view thereof;

FIG. 6 is a front view thereof; and,

FIG. 7 is a rear view thereof.

Broken lines are used to show a cable connector, a cable and an interior of the strain relief, all of which form no part of the claimed design.
